UNITED STATES PATENT OFFICE.

JOHN A. HENDERSON AND JAMES D. HENDERSON, OF TINGLEY, IOWA.

WIRE-FENCE REEL.

SPECIFICATION forming part of Letters Patent No. 423,764, dated March 18, 1890.

Application filed October 17, 1889. Serial No. 327,264. (No model.)

To all whom it may concern:

Be it known that we, JOHN A. HENDERSON and JAMES D. HENDERSON, citizens of the United States, residing at Tingley, in the county of Ringgold and State of Iowa, have invented a new and useful Wire-Fence Reel, of which the following is a specification.

This invention has relation to reels for taking up and paying out barbed wire either in the construction of a fence or in its removal from one place to another, and among the objects in view are to provide a light conveniently and economically constructed reel adapted to wind and pay out wire and to provide a uniform tension for the wire, whereby the same is taken up or paid out in a uniform manner, all as will hereinafter appear, and be particularly pointed out in the claims.

Referring to the drawings, Figure 1 is a perspective of a reel constructed in accordance with our invention; Fig. 2, a central longitudinal section; Fig. 3, a detail in perspective of the vertically-sliding tension-sash.

Like numerals of reference indicate like parts in all the figures of the drawings.

In practicing our invention we construct a truck, and the same comprises opposite side bars 1, which at their rear ends terminate in ordinary barrow-handles 2 and are connected at intervals by a series of oppositely-arranged transverse connecting-bars 3, the rear one of which is provided with a central longitudinal slot 4. An axle 5 connects the bars at their forward ends and is provided with a pair of ordinary supporting-wheels 6. A pair of legs 7 are pivotally connected to about the center of each of the bars and serve as a support for the rear end of the truck, the legs being capable of being folded up out of position and against the sides of the bars. Side pieces 9 are secured to the upper edges of the bars, and are connected at their upper ends by a cross-strip 10. The front edges of these side pieces are provided with vertical ways 11, and in the same there is mounted for vertical reciprocation a sliding sash 12. The sash 12 comprises opposite side bars 13, which slide in the ways, and a connecting-frame 14, having a central transverse slot 15, extending from one way to the other. The upper rail of the frame extends rearwardly, and by striking against

the cross-strip connecting the side pieces serves to limit the upward movement of the tension-sash, the ways being closed at their lower ends and limiting its downward movement.

16 represent opposite bearing-standards securely bolted to the side pieces 9 and bars 1. The upper ends of the standards project above the rear inclined edges of the side pieces and are provided with bearings 17, one of which is provided with a brake-lever 18, the end of which extends to the rear and comes within easy grasp of a person pushing or drawing the reel. Within the bearings is mounted a removable reel-shaft 19, upon which the brake-lever is designed to act, and upon the shaft is mounted a reel 20, the opposite ends of the shaft being squared to receive a removable crank 22, whereby the shaft 70 and reel may be operated from either side of the machine.

The operation of the invention is as follows: To take up a fence one terminal of the wire is connected with one of the arms of the reel 75 and the reel is revolved. As the truck approaches the nearest fence-post the wire is disconnected and the operation repeated to the next post. As the wire is wound upon the reel it passes through the transverse slot 80 in the tension-sash, which assumes a position relative to the amount of wire and consequent diameter of the roll of wire. When the wire has been wound upon the reel, if it be desired to set up the fence at some other point, the 85 truck is rolled to said point and the loose terminal of the wire made fast to the first post or to some snag or other fixed object. The brake is now put on to give the required tension to the wire as it is paid out and a strap 90 or rope passed through the small central slot of the rear bar-connecting strip, which strap is connected to a strap 24, which is passed around the shoulders of the operator, who grasps the handles and draws the truck to 95 the rear.

In constructing wire fences from rolls of wire an ordinary journal takes the place of the reel-shaft, and the operation is essentially the same as before described.

It will be apparent that the tension-sash will accommodate itself in the ways auto-

matically to the amount of wire upon the reel, thereby insuring an even tension, said frame being weighted or constructed of heavy material to provide for such tension.

5 Having described our invention, what we claim is—

1. In a reel-cart, the combination, with the truck provided with reel-bearings and ways mounted at one side of said bearings, of the transverse vertically - reciprocating frame mounted in the ways and provided with a slot for the passage of the wire, substantially as specified.

2. In a reel-cart, the combination, with the truck provided with reel-bearings and opposite side pieces provided at one end with opposite guides, of a sash mounted for sliding

in the guides and consisting of upper and lower transverse rails and vertical connecting-rails, the upper transverse rail being projected laterally beyond one side of the sash, and a cross-strip connecting the upper ends of the side pieces and arranged in the path of said projected upper sash-rail, substantially as specified. 20

In testimony that we claim the foregoing as our own we have hereto affixed our signatures in presence of two witnesses.

JOHN A. HENDERSON:
JAMES D. HENDERSON.
